UNITED STATES PATENT OFFICE.

MAG DOE, OF BERKELEY, CALIFORNIA.

DESIGN FOR A PENCIL.

Application filed December 12, 1923. Serial No. 7,996. Term of patent 3½ years.

To all whom it may concern:

Be it known that I, MAG DOE, a citizen of Canada, and a resident of Berkeley, county of Alameda, State of California, have invented a new, original, and ornamental Design for a Pencil, of which the following is a specification, reference being had to the accompanying drawings, forming part thereof.

Fig. 1 is a front elevation of the pencil showing my new design,

Fig. 2 is a back elevation of a pencil showing my new design.

I claim:

The ornamental design for a pencil, as shown.

In testimony whereof I have signed this specification at Berkeley, California, this 6th day of December, 1923.

MAG DOE.
